UNITED STATES PATENT OFFICE.

ALBERT R. LACHE, OF NEWARK, NEW JERSEY, ASSIGNOR TO THE
WHITEHEAD AND HOAG COMPANY, OF SAME PLACE.

DESIGN FOR A POCKET-PIECE.

SPECIFICATION forming part of Design No. 34,523, dated May 21, 1901.

Application filed April 15, 1901. Serial No. 56,008; Term of patent 3½ years.

To all whom it may concern:

Be it known that I, ALBERT R. LACHE, a citizen of the United States, residing at No. 8 Elmwood avenue, in the city of Newark, county of Essex, and State of New Jersey, have invented and produced a new and original Design for a Pocket-Piece, of which the following is a specification, reference being had to the accompanying drawings, forming a part thereof, and in which—

Figure 1 shows a top plan view of the piece. Fig. 2 is a cross-section on line xx , Fig. 1.

As shown in the drawings, the leading or material feature of my design consists in an oval disk truncated at one end and provided with a central opening. The outer edge of the disk a is provided with a bead b , representing a wishbone, and upon the face of the disk is a raised portion c , extending around

the opening e and of substantially the same form as the disk itself, representing a horseshoe, and d is a four-leafed clover upon the face of the disk and at one end thereof uniting the apex of the wishbone and the horseshoe, the whole forming a unique unitary design for a pocket-piece.

Having thus described my invention, what I claim, and desire to secure by Letters Patent, is—

The design for a pocket-piece substantially as herein described and shown.

In witness whereof I have hereunto set my hand this 12th day of April, 1901.

ALBERT R. LACHE.
